UNITED STATES PATENT OFFICE.

ALOIS BENJAMIN SALIGER, OF NEW YORK, N. Y., ASSIGNOR, BY MESNE ASSIGNMENTS,
TO THE BECK DUPLICATOR COMPANY, A CORPORATION OF NEW YORK.

DUPLICATOR.

1,254,733.

Specification of Letters Patent. Patented Jan. 29, 1918.

Application filed May 9, 1916. Serial No. 96,465.

To all whom it may concern:

Be it known that I, ALOIS BENJAMIN SALIGER, a citizen of the United States, and a resident of the borough of Manhattan, in the city and State of New York, have invented certain new and useful Improvements in Duplicators, of which the following is a specification.

The invention relates to duplicators, and more particularly to such machines provided with a duplicating surface, usually of a gelatinous nature, adapted to receive negative or reversed impressions, and rolling means for bringing a sheet of paper or the like into contact with such duplicating surface, in order that such impression may be communicated from said surface to said paper.

Some of the principal objects of the invention are to provide a machine of the type mentioned which shall be efficiently, easily, and quickly operated; comparatively noiseless, and in which the operation of stripping the paper from the duplicating film after it has received its impression shall be smooth and certain in action.

The invention consists in the novel construction, arrangement and combination of various devices, elements and parts, as shown in the accompanying drawings and fully described in this specification.

In the said drawings, Figure 1 is a side elevation of a duplicator constructed according to my invention; Fig. 2 is a plan view of the same; Fig. 3 is a section taken on the line 3—3 of Fig. 2; Fig. 4 is a section taken on the line 4—4 of Fig. 1 and looking in the direction of the arrows; Figs. 5, 6, and 7 are detail views to be hereinafter described; and Figs. 8, 9, 10 and 11 are diagrammatic views showing the operation of my invention.

In carrying my invention into effect in the embodiment thereof which I have selected for illustration in the accompanying drawings, I provide a frame comprising inner side members 20, having integral therewith legs 21 by means of which it is adapted to be supported on a table or other suitable support, and if desired rigidly secured thereto, and also having racks 24; end members 22; and outer side members 25, preferably in the form of cylindrical rods bearing on their upper sides racks 23. The inner side

members 20 may if desired be integral with the end members 22, the latter being provided in their ends, which project beyond the inner side members 20, with sockets adapted to receive the rods 25, which may slide in said sockets, but which may when desired be secured against such sliding by screws, pins, or the like. This construction is provided in order that the rods 25 may be partially or entirely removed from the frame in order to attach or remove the movable frame or carriage which will be hereinafter described, to the stationary portion of the apparatus.

Extending between the inner side members 20 is a bed 33, having suitably stretched thereover a suitable cover or strip of fabric 19, and over which passes the duplicating film 41. The ends of the duplicating film pass downward over rollers 18 at the ends of the bed 33, and the portion of the film not in use is stored or wound upon rollers 34, journaled in the side members 20, the detailed construction and operation of which will be hereinafter described.

The movable frame or carriage above referred to comprises side members 26 adapted to slide on the rods 25, rollers 28 being provided if desired. These rollers are provided with bearing screws 35 whereby their pressure upon the rods 25 may be adjusted. These side members 26 are connected by means of a paper stop 27, and also have pivotally secured thereto swinging side members 29, connected together by means of an operating handle 30. These swinging members are supported on pivots 32 bearing in vertical slots 36 in the members 26, and may be adjusted by means of bearing screws 37. A paper platform 31 may be provided extending from the members 26, although this is not essential and may be dispensed with if desired.

Referring now more particularly to Fig. 3, it will be seen that the members 29 are each provided with a vertical rectilinear slot 38, in which slots slide blocks 39, having journaled therein the ends of an impression roller 40. Springs 42 are provided having one end secured to the members 29, and the other bearing against the blocks and forcing the same downward. The pressure of these springs may be regulated by means of bearing screws 43. I also provide stripping

rollers 44 and 45, preferably having their surfaces slightly roughened so that they will engage with each other. These rollers are coupled together by means of links 46 (see Fig. 4) 5 in which they are rotatably mounted, these links having portions 47 extending beyond the roller 45, which portions are formed into cams, as in Fig. 3. The ends of the roller 44 are mounted in blocks 48 secured in the 10 members 29, and to each end of the said roller 44 is rigidly secured a wheel 49 adapted to run upon the top edge of one of the side members 20 of the stationary frame and provided with a toothed portion adapted to 15 engage with the rack 24, the detailed construction of these wheels being shown in Figs. 6 and 7. By reference to these figures it will be seen that the teeth of said wheels 49, designated 50, do not extend to the full 20 depth of the rack 24, thus minimizing the noise made by the engagement of the teeth with the rack. Secured between the members 29 and located above the stripping rollers 44 and 45 is a paper guide 51. The 25 stationary frame is provided with two sets of bearing surfaces 52 and 53, adapted to coact with the cams 47 in a manner to be hereinafter described.

In order to adapt the apparatus for use 30 with sheets of paper of different sizes, it is desirable to provide means for limiting the extent of the movement of the carriage, in other words, for fixing the point where the operating stroke of the carriage shall begin, 35 so that the end of the paper which is last depressed by the impression roller will project slightly beyond the end of the bed and duplicating film, in order that it may be engaged by the stripping rollers on the return 40 stroke of the carriage. For this purpose I provide adjustable stops on the rods 25. The construction of one of these stops is shown in detail in Fig. 5. It consists of a piece 54, provided with a perforation 55 by means of 45 which it is adapted to slide on its rod 25, and with a vertical perforation 56 having a shoulder 57. The upper portion of the piece 54 is forked as shown more particularly in Fig. 1. I provide an L-shaped pin 50 58, one arm of which occupies the perforation 56, and the other arm the upper notched portion mentioned above. The first named arm is provided with a head 59, between which and the shoulder 57 acts a helical 55 spring 60. This spring 60 normally holds the pin 58 in the position shown in Fig. 5, that is, with its horizontal arm slightly below the level of the top of the perforation 55. When in this position it will engage 60 with one of the notches of the rack 23, and the stop will be held against movement. When it is desired to shift the stop, the head 59 is pressed upward, compressing the spring 60, and lifting the horizontal arm of the 65 pin 58 clear of the rack 23. The stop may

then be moved into any desired position, and will be automatically secured against movement upon the release of the head 59.

The members 20 are provided at their ends toward the right of Figs. 1, 2 and 3, with 70 raised portions 120, which are adapted, as the carriage comes to the right-hand end of its stroke, to raise the impression roller slightly, in order that it may not bear upon the portion of the paper which projects beyond the end of the duplicating film. 75

The end portions of the duplicating film 41 which are not in use, are as hereinbefore set forth, stored upon rollers 34. These rollers are removable, and one end of each 80 roller is rotatably mounted in a socket in one of the members 20. The other end is non-rotatably journaled in a rotatable socket member 61 mounted in the other member 20. This socket-member is provided with a 85 ratchet wheel 63, and with a handle 64 by means of which it may be rotated.

I provide pawls 65 adapted to engage with the ratchets 63, said pawls being pivoted at 66 to the support 20. Each pawl is 90 provided with a spring 67. Rods 68 are provided, pivotally secured together by means of a pin 69 which works in a vertical slot 70 in the member 20. This pin 69 is provided with a friction-washer 169 (see Fig. 2) 95 which presses the rods 68 against the outer portion of the pin. By this arrangement the pin 69 will remain in any position in which it may be placed. The other ends of these rods are slotted, and are slidably and 100 pivotally secured to studs on the member 20. Each rod is provided with a stud 71 adapted to bear against one of the springs 67. When the pin 69 and parts connected therewith are in the position shown in Fig. 1, the studs 71 105 depress the springs 67, and lift the ends of the pawls 65 out of engagement with their respective ratchets. When the pin 69 is at the top of the slot 70, the studs 71 are lifted away from the springs 67, and the pawls 65 110 are allowed to drop down upon their ratchets. It will thus be obvious that the pawls may be thrown either into or out of engagement with their ratchets by the operation of the pin 69. 115

The operation of my invention is as follows: The duplicating film is first placed in the machine by securing the film rollers in their bearings. The film is tightened over the bed by placing the pawls 65 120 in engagement with the ratchets 63, and rotating one or both of the handles 64. When it is desired to bring into play a fresh portion of the duplicating film, the pawls are disengaged, and either of the handles 125 64 may be rotated in either direction to the extent desired, when the pawls may be again placed in engagement with their ratchets, and the film tightened in the manner above set forth. 130

The duplicating film being secured in place, and the carriage being moved to the end of the machine which is shown at the left of Figs. 1, 2 and 3, a sheet of paper bearing in suitable copying ink the matter to be duplicated is placed face downward upon the support 31, with its edge against the stop 27. The mechanism will then be in the position shown in Fig. 8. It will be observed that the two stripping rollers lie in a horizontal plane, the cams 47 resting on the top of the bed 33.

The handle 30 is then moved toward the right. The first effect of this is to depress the roller 40 upon the end of the paper (designated 101), bringing the same into contact with the duplicating film and forcing it below the edge of the stop 27. The parts will then be in the position shown in Fig. 9.

The movement of the handle 30 is continued until the carriage is in the position shown in Figs. 1, 2, and 3, and diagrammatically in Fig. 10. During this impression stroke the constant pull toward the right of the drawings keeps the members 29 and attached parts in the position relative to the horizontal shown in Fig. 9, but when this pull is discontinued, the parts are free to assume the position shown in the said Fig. 10. The impression roller has passed over the entire paper, and the greater part of said paper lies in contact with the duplicating film. It will be observed that when the carriage is in this position

the stripping rollers occupy a vertical plane, the cam 47 being guided downward by the surface 53 as the carriage nears the end of this stroke. The stops 54 should occupy such a position that the end of the paper, after the impression roller has passed entirely thereover, shall project slightly beyond the right hand edge of the bed, as shown at 102 in Fig. 10. The impression roller is lifted up as it comes to the right hand end of its stroke, by the raised portions 120, which prevent it from bearing upon the portion of the paper which projects beyond the duplicating film. This portion of the paper is not forced downward by the impression roller, but is permitted to project horizontally, where it may be grasped by the stripping rollers.

The movement of the carriage is then reversed, the leftward pull upon the handle 30 maintaining the members 29 and attached parts in the position relative to the horizontal shown in Figs. 10 and 11. The projecting end of the paper is caught between the stripping rollers 44 and 45, and these rollers are immediately thereafter swung into a horizontal plane by the action of the cam 47 against the surface 52. As the paper is passed out between these rollers it strikes against the guide 51 and is so deflected as to pass over the impression roller 40 and

to slide upon the support 31. Fig. 11 shows diagrammatically the position of the parts after the return stroke is begun.

The return movement of the carriage is continued until the carriage strikes against the stops 54. The result of this operation is to return the paper to the support 31, an impression having been transferred from the paper to the duplicating film by the impression roller 40. The desired number of copies may then be transferred from the said film to fresh sheets of paper by passing them through the machine in the same manner as the sheet bearing the original impression is passed through.

The advantages of my invention will be obvious from what has been above set forth concerning its construction and mode of operation. A very important advantage is obtained by the use of the various bearing screws (35, 37, and 43) by which all lost motion may be taken up, and by providing the wheels 49 with a tread portion adapted to run upon the top of the members 20, permitting the use of gear teeth which do not engage to the full depth of the rack; instead of employing merely a rack and gear wheel. All these factors contribute to the endurance of the machine, and to its easy and noiseless operation. The stripping rollers are out of gear with the rack 24 during the impression stroke, thus eliminating wear on the parts and unnecessary noise.

I do not limit myself to the embodiments of my invention herein set forth and shown in the accompanying drawings, as it is obvious that various modifications therein can be made without departing from the spirit and scope of my invention. For instance the carriage, which has been described as sliding upon rods, may be merely mounted upon wheels and roll over the bed of the machine. Various modifications will suggest themselves to those skilled in this art.

Having thus described my invention, what I claim as new and desire to secure by Letters Patent is as follows:

1. In a duplicator, the combination with a frame having a bed and a duplicating medium thereon; of a carriage movably mounted on said frame and provided with means adapted to depress a sheet of paper or the like on to said duplicating medium and with means adapted to strip same from said medium, said stripping means comprising a pair of rollers pivotally secured to said carriage and adapted to lie side by side with their line of contact approximately in the plane of said duplicating medium one roller on one side of said plane and the other roller on the other side of said plane at the beginning of the stripping operation whereby a sheet of paper on said medium may enter between said rollers, but said stripping roll-

ers being adapted to be swung out of said relation to said plane after said stripping operation has been begun.

2. In a duplicator, the combination with a frame having a bed and a duplicating medium thereon; of a carriage movably mounted on said frame and provided with means adapted to depress a sheet of paper or the like on to said duplicating medium and with means adapted to strip same from said medium, said stripping means comprising a pair of rollers pivotally secured to said carriage and adapted to lie side by side with their line of contact approximately in the plane of said duplicating medium one roller on one side of said plane and the other roller on the other side of said plane at the beginning of the stripping operation whereby a sheet of paper on said medium may enter between said rollers, but said stripping rollers being adapted to be swung out of said relation to said plane after said stripping operation has been begun; said frame being provided with a rack and one of said stripping rollers being provided with a gear adapted to engage with said rack.

3. In a duplicator, the combination with a frame having a bed and a duplicating medium thereon; of a carriage movably mounted on said frame and provided with means adapted to depress a sheet of paper or the like on to said duplicating medium and with means adapted to strip said sheet of paper from said medium, said stripping means comprising a pair of rollers pivotally secured to said carriage said rollers at the beginning of the stripping operation lying side by side and with their line of contact approximately in the plane of said duplicating medium one roller on one side of said plane and the other roller on the other side of said plane whereby a sheet of paper on said medium may enter between said rollers; and means adapted to swing said rollers out of said relation to said plane when the stripping operation has been begun, whereby said sheet of paper is separated from said medium.

4. In a duplicator, the combination with a frame having a rack, a bed, and a duplicating medium on said bed; of a carriage movably mounted on said frame and provided with means adapted to depress a sheet of paper or the like on to said duplicating medium and with means adapted to strip same from said medium; of an adjustable stop adapted to limit the movement of said carriage upon said frame, said stop comprising a member movably mounted on said frame and a pin movable in said movable member adapted normally to engage with said rack.

5. In a duplicator, the combination with a frame having a rack, a bed, and a duplicating medium on said bed; of a carriage movably mounted on said frame and provided

with means adapted to depress a sheet of paper or the like on to said duplicating medium and with means adapted to strip same from said medium; of an adjustable stop adapted to limit the movement of said carriage upon said frame, said stop comprising a member movably mounted on said frame and a pin movable in said movable member and provided with a projecting toe adapted to engage with said rack. 70

6. In a duplicator, the combination with a frame having a rack, a bed, and a duplicating medium on said bed; of a carriage movably mounted on said frame and provided with means adapted to depress a sheet of paper or the like on to said duplicating medium and with means adapted to strip same from said medium; of an adjustable stop adapted to limit the movement of said carriage upon said frame, said stop comprising a member movably mounted on said frame and a pin movable in said movable member and provided with a projecting toe adapted to engage with said rack and a spring adapted to bring about such engagement. 75

7. In a duplicator, the combination with a frame having a bed and a duplicating medium thereon; of a carriage movably mounted on said frame and provided with means adapted to depress a sheet of paper or the like on to said duplicating medium, and with a pair of rollers adapted to strip same from said medium; means adapted to elevate said depressing means as it finishes its stroke, so that it is prevented from then depressing the part of said sheet of paper adjacent thereto on to said duplicating medium. 90

8. In a duplicator, the combination with a frame having a bed and a duplicating medium thereon; of a carriage movably mounted on said frame and provided with means adapted to depress a sheet of paper or the like on to said duplicating medium, and with a pair of rollers adapted to strip same from said medium; said frame being provided with tracks upon which the ends of said depressing means are adapted to run, said tracks being elevated at the point where the said depressing means finishes its stroke whereby the said depressing means toward the end of its stroke is raised up and prevented from then depressing the part of said sheet of paper adjacent thereto on to said duplicating medium. 105

9. In a duplicator, the combination with a frame having a bed and a duplicating medium thereon; of a carriage movably mounted on said frame and provided with means adapted to depress a sheet of paper or the like on to said duplicating medium; and with means adapted to strip same from said medium, said stripping means comprising a pair of rollers; said frame being provided with tracks upon which the ends of one of 110

120

125

130

5 said stripping rollers are adapted to run and being also provided with a rack, and said before-mentioned one of said stripping rollers being provided with a gear adapted to engage with said rack; and means adapted to prevent the teeth of said gear and of said rack from meshing to their full extent.

10. In a duplicator, the combination with a frame having a bed and a duplicating medium thereon; of a carriage movably mounted on said frame and provided with means adapted to depress a sheet of paper or the like on to said duplicating medium; and with means adapted to strip same from 15 said medium, said stripping means comprising a pair of rollers; said frame being provided with tracks upon which the ends of one of said stripping rollers are adapted to run and being also provided with a rack, 20 and said before mentioned one of said stripping rollers being provided with a gear adapted to engage with said rack; the said tracks being of such elevation as to prevent the teeth of said gear and of said rack from 25 meshing to their full extent.

11. In a duplicator, the combination with a frame having a bed and a duplicating medium thereon; of devices adapted to store portions of the duplicating medium not in 30 use and to shift the said medium when desired over the said bed and to hold the same taut thereupon, said devices comprising rollers journaled in said frame, rotating means for said rollers, co-acting ratchets and pawls 35 adapted to hold said rollers against rotation, and means adapted to release said pawls, said means comprising bars pivoted in said frame and adapted when swung in one position to allow said pawls to engage 40 with said ratchet and when swung into another position to prevent said pawls from so engaging, the ends of said bars being pivotally secured together whereby they may be simultaneously operated.

45. 12. In a duplicator, the combination with a frame having a bed and a duplicating medium thereon; of devices adapted to store portions of the duplicating medium not in use and to shift the said medium when desired over the said bed and to hold the same taut thereupon, said devices comprising rollers journaled in said frame, rotating means for said rollers, co-acting ratchets and pawls 50 adapted to hold said rollers against rotation and means adapted to release said pawls, said means comprising bars pivoted in said frame and adapted when swung in one position to allow said pawls to engage with said ratchets and when swung into another position to prevent said pawls from so engaging, the ends of said bars being pivotally secured together whereby they may be simultaneously operated and being provided with 55 means adapted to hold same in any position 60 in which they are placed.

13. In a duplicator, the combination with a frame having a bed and a duplicating medium thereon; of devices adapted to store portions of the duplicating medium not in use and to shift the said medium when desired over the said bed and hold the same taut thereupon, said devices comprising rollers journaled in said frame, rotating means for said rollers, co-acting ratchets and pawls adapted to hold said rollers against 70 rotation, springs adapted to bear upon said pawls and hold them normally in engagement with said ratchets and means adapted to release said pawls, said means comprising bars pivoted in said frame and adapted 75 when swung in one position to allow said pawls to engage with said ratchets and when swung into another position to prevent said pawls from so engaging.

14. In a duplicator, the combination with 80 a frame having a bed and a duplicating medium thereon; of a carriage movably mounted on said frame provided with rocking members pivotally secured thereto, a roller adapted to depress a sheet of paper or the 85 like on to said duplicating medium journaled in said rocking members on one side of the pivotal connection thereof, and a pair of rollers adapted to strip said sheet of paper from said medium, rotatably secured 90 to said rocking members on the other side of said pivotal connection.

15. In a duplicator, the combination with a frame having a bed and a duplicating medium thereon; of a carriage movably 100 mounted on said frame and provided with means adapted to depress a sheet of paper or the like onto said duplicating medium and with means adapted to strip same from said medium, said stripping means comprising a 105 pair of rollers secured to said carriage and adapted to lie side by side with their line of contact approximately in the plane of said duplicating medium one roller on one side of said plane and the other roller on the 110 other side of said plane at the beginning of the stripping operation whereby a sheet of paper on said duplicating medium may enter between said rollers, but said stripping rollers being adapted to be swung out of said 115 relation to said plane after said stripping operation has been begun.

16. In a duplicator, the combination with a frame having a bed and a duplicating medium thereon; of a carriage movably mounted on said frame and provided with means adapted to depress a sheet of paper or the like on to said duplicating medium and with means adapted to strip same from said medium, said stripping means comprising a 120 pair of rollers secured to said carriage and adapted to lie side by side with their line of contact approximately in the plane of said duplicating medium one roller on one side of said plane and the other roller on the 125 130

other side of said plane at the beginning of the stripping operation whereby a sheet of paper on said medium may enter between said rollers, but said stripping rollers being 5 adapted to be swung out of said relation to said plane after said stripping operation has been begun; said frame being provided with a rack and one of said stripping rollers being provided with a gear adapted to engage 10 with said rack.

17. In a duplicator, the combination with a frame having a bed and a duplicating medium thereon; of a carriage movably mounted on said frame and provided with means 15 adapted to depress a sheet of paper or the like on to said duplicating medium and with means adapted to strip said paper from

said medium, said stripping means comprising a pair of rollers secured to said carriage said rollers at the beginning of the stripping 20 operation lying side by side with their line of contact approximately in the plane of said duplicating medium, one roller on one side of said plane and the other roller on the other side of said plane, whereby a sheet 25 of paper on said medium may enter between said rollers; and means adapted to swing said rollers out of said relation to said plane when the stripping operation has been begun, whereby said sheet of paper is separated from said medium.

In witness whereof I have hereunto signed my name this 3d day of May, 1916.

ALOIS BENJAMIN SALIGER.
